(57) **CLAIM**

The ornamental design for a probe for photoacoustic measurement device, as shown and described.

DESCRIPTION

FIG. 1 is a top, front, right perspective view of a probe for photoacoustic measurement device showing our new design; FIG. 2 is a front view thereof; FIG. 3 is a rear view thereof; FIG. 4 is a right side view thereof; and, FIG. 5 is a top view thereof.

(Continued)

The broken lines showing the remainder of the probe for photoacoustic measurement device are for environmental purposes only and form no part of the claimed design.

1 Claim, 1 Drawing Sheet
